US0D1011315S

(12) **United States Design Patent** (10) **Patent No.:** **US D1,011,315 S**
(45) **Date of Patent:** **** Jan. 16, 2024**

(54) **EARPHONE**

(71) Applicant: **HUAWEI TECHNOLOGIES CO., LTD.**, Guangdong (CN)

(72) Inventors: **Jie Huang**, Shanghai (CN); **Zengzhu Deng**, Shanghai (CN); **Qiang Huang**, Shenzhen (CN)

(73) Assignee: **HUAWEI TECHNOLOGIES CO., LTD.**, Shenzhen (CN)

(**) Term: **15 Years**

(21) Appl. No.: **29/785,283**

(22) Filed: **May 25, 2021**

(30) **Foreign Application Priority Data**

Nov. 27, 2020 (CN) 202030726020.3

(51) **LOC (14) Cl.** **14-01**

(52) **U.S. Cl.**

USPC **D14/223**

(58) **Field of Classification Search**

USPC D14/223, 205, 206; D24/174, 217, 218; 128/864, 865, 866; 181/129, 130, 135; 379/430, 431; 381/380, 381, 322-324, 381/330; 455/90.3, 575, 1, 569.1; D9/415, 432, 721; D3/274, 294; D13/108

Primary Examiner — Katie Jane Stofko

(57) **CLAIM**

The ornamental design for an earphone, as shown and described.

DESCRIPTION

FIG. 1 is a top perspective view of an earphone showing our new design;

FIG. 2 is a bottom perspective view thereof;

FIG. 3 is a front view thereof;

FIG. 4 is a back view thereof;

FIG. 5 is a top view thereof;

FIG. 6 is a bottom view thereof;

FIG. 7 is a right side view thereof; and,

FIG. 8 is a left side view thereof.

The broken lines in drawings show portions of the earphone that form no part of the claimed design.

1 Claim, 8 Drawing Sheets
